JOHN MARTINO, JACOB BEESLEY, AND JOHN CURRIE, OF PHILADELPHIA,
PENNSYLVANIA.

Design No. 2,971, dated March 31, 1868; antedated February 11, 1868.

DESIGN FOR A COOK'S STOVE.

The Schedule referred to in these Letters Patent and making part of the same.

TO ALL WHOM IT MAY CONCERN:

Be it known that we, JOHN MARTINO, JACOB BEESLEY, and JOHN CURRIE, of the city of Philadelphia, in the county of Philadelphia, and State of Pennsylvania, have originated and designed a new Pattern for Cook-Stove or Portable Range, of which the following is a full, clear, and exact description, reference being had to the accompanying specimens or drawings, making part of this specification.

First. Figure 1, front of stove-panel A, with ornamented panel-centre of French rosette, connecting ornamented pods of same style with short points at corners of panel.

Second. Figure 2, B and C, oven-doors, with ornamented panel-centre of same style as fig. 1, connecting ornamented pods with ornamented points, extending to corners of door-moulding.

Third. Figure 3, D, ornamented same as B and C.

Fourth. Figure 4, E, bottom plate, with corrugated bead-moulding extending along front edge.

Fifth. Foot F, with lap extending down, with ornamented pod attached.

What we claim as our invention, and desire to secure by Letters Patent, is—

The design for a portable range, as set forth and shown.
